UNITED STATES PATENT OFFICE

LUIGI PAVIA, OF ALLENTOWN, PENNSYLVANIA

AUTOMATIC LOOM SHUTTLE

Application filed August 9, 1930. Serial No. 474,139.

This invention relates to shuttles for looms equipped with electro-magnetic means to stop the same on substantial depletion of weft in the shuttle and particularly to that class of such shuttles in which depletion of the weft is responsible for movement of a circuit-closer incorporated in the shuttle.

Given a shuttle of the class indicated having a spindle-including electro-conductive system provided with a terminal, another electro-conductive system arranged in the shuttle and having a terminal and a contact, a removable quill or other core for the weft windings arranged on the spindle and having a lateral aperture, and a circuit closer movable on the spindle within the core and projecting through said aperture and normally urged to move into contact with said contact but held from such movement by the windings, my invention contemplates providing the shuttle (as the spindle thereof) and core with co-engaging means to determine registry of the core aperture with the circuit closer on placing the core on the spindle and thereupon hold the core against rotation on the spindle so as not to strain or incapacitate the circuit-closer. My invention further contemplates avoiding weakening the butt end of the core, and this I accomplish by terminating said aperture short of said butt end of the quill, leaving said end annularly intact, and adapting the circuit closer to protrude through said end.

In the drawings, Fig. 1 is a longitudinal horizontal section through a loom shuttle-box, showing the improved shuttle therein in plan;

Fig. 2 is a similar view of the box and shuttle;

Fig. 3 is a side elevation of the shuttle;

Fig. 4 a vertical longitudinal section thereof, with certain parts in side elevation;

Fig. 5 a similar view with some of said parts in section;

Fig. 6 is a butt-end view of the core.

1 is the shuttle body having some (metal) spindle-including structure here comprising the following parts: The spindle 2, the clips 3 having hooked ends 3a to engage the en-

50 larged butt of the quill and hold the latter

from endwise displacement on the spindle, the same receiving the butt of the spindle between them and being entered into mortises 1a in the shuttle body; the pin 4 on which the spindle butt is pivoted and the stop-pin 5 to limit downward pivotal movement of the spindle, both such pins being mounted in the clips; and the spring 6 to hold the spindle elevated or depressed, being supported by pins 8 in the clips. Slipped onto the spindle is a core 9 for the windings, being here a wooden quill having a head 9a to be received by the hooks 3a when the spindle is depressed. So much is the usual construction.

The portion of the spindle which includes its butt here also includes an enlargement 10, and the spindle has a longitudinal slit 11 which opens forwardly and rearwardly except at its left-hand end where, within the enlargement, it is open only forwardly. In this slit is pivoted, at 12, a longitudinally extending metal circuit-closer 13 in the form of a lever of the second class the left-hand end of which is backed by a spring 14 set in a socket in the enlargement and which normally tends to turn the lever in the direction in which its left-and-right-hand ends would respectively protrude from the slit at front and rear. The right-hand end of the lever is rearwardly rounded, as at 13a, and its left-hand end has a forward projection 13b whose extremity is permanently exterior of the enlargement and is bent up, as at 13c. Opposite this bent-up end is the contact 15 which is here a stud projecting inwardly from one of two metal plates 16 set in the front face of the shuttle body and through a notch 3b in the adjoining hook 3a (without contact therewith), the other plate being connected with said hook by a wire 17.

The spindle-including structure, wire and plate form one of the mentioned electro conductive systems and the other plate and contact 15 form the other of said systems, the terminals (16) of which are adapted to be connected by the circuit-closer.

The quill has a slot aperture 18 to receive the rearwardly protruding portion of lever 13 when the quill is fully home on the spindle. If the quill is fully wound the windings a

thereon hold the circuit closing lever in the position of Fig. 2, with said circuit open; but when the mass of windings becomes appreciably depleted the spring 14 will shift the lever to close the circuit at 13c—15.

5 At 19 is shown the shuttle box of a loom having the terminals 20 of a partial circuit 21 which contains a source of energy 22 and any well known means, shown diagrammatically at 23, for stopping the loom.

10 Each time the shuttle enters the box its plates 16 make contact with the terminals 20. So long as sufficient windings remain on the quill the circuit then constituted by the indicated partial circuits in and extraneous of the shuttle remains open at 13a—15; but if this circuit is there closed because depletion of the windings has released the circuit-closer means 23 will be energized and stop the loom.

15 When the quill is placed on the spindle its aperture 18 is concealed by the windings. In order that the weaver may determine that the aperture and circuit-closer register, and also

20 to prevent his turning the quill after the circuit-closer has sprung into the aperture (and possibly straining the parts, as the circuit-closer and quill and rendering them inoperative), I provide the spindle-including structure and quill with an interengaging projection 24 and recess 25. If the aperture registered with the circuit-closer before the interlock was effected at 24—25 there would be opportunity to turn the quill and in some

25 way injure the parts, although when the quill was fully home the interlock would prevent this; but as shown this is avoided by forming the aperture to extend sufficiently short of the butt end of the quill so that the 30 interlock occurs before the circuit-closer registers with and so is released by the aperture. Further, by extending said aperture short of the butt end of the quill said end is left annularly intact and the quill is therefore not 35 appreciably weakened.

Having thus fully described my invention what I claim is:

1. A shuttle of the class described having a spindle-including electro-conductive system provided with a terminal, another electro-conductive system arranged in the shuttle and having a terminal and a contact, a removable core for the left windings arranged on the spindle and having a lateral aperture, 50 and a circuit-closer movable on the spindle within the core and projecting through said aperture and normally urged to move into contact with said contact but held from such movement by the windings, said shuttle and 55 core having co-engaging means to determine registry of the core-aperture with the circuit-closer on placing the core on the spindle and thereupon hold the core against rotation 60 on the spindle and said aperture extending 65 sufficiently short of the butt end of the quill

so that when the latter is slipped on the spindle said means will interengage before said circuit-closer is cleared by the aperture.

2. In combination, a shuttle body, a core for the weft windings having a lateral aperture, an electro-conductive system arranged in the body and having a terminal and a contact, and another electro conductive system including a metallic core-retaining clip fixed in said body, a metallic pivoted spindle in contact with the clip, and a metallic circuit closer movable on the spindle within the core and normally urged to move through said aperture into contact with said contact but held therefrom by the windings, and a second terminal electrically connected to the clip. 70

3. In combination, a shuttle body, a core for the weft windings having a lateral aperture, an electro-conductive system arranged in the body and having a terminal exterior of the body and a contact within the body, and another electro-conductive system including a metallic core-retaining clip fixed in said body and penetrated by the first system without contact therewith, a metallic pivoted spindle in contact with the clip, and a metallic circuit closer movable on the spindle within the core and normally urged to move through said aperture into contact with said contact but held therefrom by the windings, and a second terminal electrically connected to the clip. 75

In testimony whereof I affix my signature.

LUIGI PAVIA.
